(57) **CLAIM**

The ornamental design for a work light as shown and described.

DESCRIPTION

FIG. 1 is a top perspective view of a work light, illustrating the work light in a first configuration.

FIG. 2 is a bottom perspective view of the work light of FIG. 1.

FIG. 3 is a left-side view of the work light of FIG. 1.

FIG. 4 is a right-side view of the work light of FIG. 1.

FIG. 5 is a front view of the work light of FIG. 1.

FIG. 6 is a rear view of the work light of FIG. 1.

FIG. 7 is a top view of the work light of FIG. 1.

FIG. 8 is a bottom view of the work light of FIG. 1; and,

FIG. 9 is a top perspective view of the work light of FIG. 1, illustrating the work light in a second configuration.

The broken lines illustrate portions of the work light that form no part of the claimed design.

1 Claim, 9 Drawing Sheets
